UNITED STATES PATENT OFFICE.

ALFRED G. HAGUE, OF DES MOINES, IOWA.

CASTER.

Application filed November 21, 1924. Serial No. 751,254.

The object of my invention is to provide a caster of simple, durable and inexpensive construction, which may be easily and quickly applied to a tubular support such as a washing machine leg, and when so applied will permit the caster to rotate freely in its mounting.

More particularly it is the object of my invention to provide an improved caster support adapted to be easily and quickly applied to a tubular leg and formed of stamped sheet metal, so arranged that the caster support may be easily and quickly applied without the use of tools, and held in position by frictionally engaging the inner surface of the tube after it has been applied.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is an end elevation of my improved caster.

Figure 2 is a side elevation of same showing the manner in which it is applied to a tubular leg, the leg being shown in section.

Figure 3 is a detail sectional view taken on the line 3-3 of Figure 2.

Figure 4 is a detail sectional view taken on the line 4-4 of Figure 2, the caster and the supporting leg being removed.

The numeral 10 indicates the lower end of a tubular leg such as used in washing machines and similar devices. My improved device comprises a disk 11 which is slightly larger than the diameter of the tube 10 and designed to support the lower end of said tube, the disk being provided with a crown portion 12 which extends upwardly into the tube 10. The members 11 and 12 form the base of the caster support.

The center of the member 12 is provided with an opening 13 for receiving the caster stem 14 which is substantially of the ordinary construction, the stem 14 being mounted in a yoke 15 in which the caster wheel 16 is pivotally mounted by means of a pin 17.

The member 12 is also provided with openings 18 designed to receive the lower ends of an inverted U-shaped frame member 19 which extends upwardly into the tubular

member 10. The upper end of the member 19 is designed to rest on the upper end of the stem 14 as clearly illustrated in Figure 1. The disk 11 and the member 19 provide means for supporting the leg 10. The upper end of the member 14 forms a pivot for the caster.

The upper end of the member 19 is formed angular so that the upper end of the member 14 rests in a channel 20 which prevents, to a certain extent, lateral movement of the stem 14 in a common plane with the downwardly extending portions of the member 19. The stem 14 is limited against lateral movement by means of a plate 21 which is mounted horizontally between the upper ends of the members 19, and the plate 21 is provided with an opening 22 to receive the upper end of the said stem 14.

The upper end of the stem 14 is formed with two bulged portions 23 which are formed in the stem, as it is placed in position by the drop forging process, and serves to prevent the stem from being pulled outwardly after it has once been placed in position. Each side edge of the plate 21 is provided with a notch 24 for receiving the members 19.

The plate 21 is formed square and of such size as to just fit the inner surface of the tubular member 10, and each end of the plate 21 is provided with a downwardly extending portion 25. Said members 25 and the plate 21 are formed of spring metal, and so formed that the lower edges of the members 25 will frictionally engage the side walls of the tube 10, which provides means for frictionally holding the caster within the tube 10. The lower ends of the members 25 are provided with inwardly extending portions 26 which overlap and are each provided with a slot 27 to receive the stem 14, the members 26 serving to limit the outward movement of the lower ends of the member 25 when the caster is removed from the leg.

By forming the bulged portion 12 with a slightly inclined surface 29, and by forming the members 25 of spring metal with their lower ends normally resting in an outwardly and downwardly extending position, it will be seen that I have provided means whereby the caster may be inserted in the lower end of the leg 10, and will be frictionally held in position by the members 25 resting against the inner surface of the leg 10, and

also the inclined portion 29 frictionally engaging the lower ends of the tube 10 in a wedge-like manner, so that when the caster has once been placed in position, it will not readily drop out.

It will further be seen that the parts are so arranged and constructed that the stem 14 will rotate freely therein. The entire weight of the supporting leg is carried on 10 the upper end of said stem 14, while lateral movement is prevented by engagement therewith by the sides of the openings 13 and 22. This provides means whereby the 15 caster stem will rotate freely, even if a considerable rust and sediment collect within the lower end of the leg 10, due to the fact that the area of contact between the stem 14 and its supports is reduced to a minimum.

I claim as my invention:

20 1. A caster designed to be detachably mounted in one end of a tubular support comprising a yoke, a caster wheel rotatively mounted in said yoke, a stem extending upwardly from said yoke, a disk pivotally 25 mounted near the lower end of said stem and perpendicular thereto, said disk being provided with an upwardly extending bulged portion having an annular inclined edge designed to fit the inner surface of said 30 tubular support, an inverted U-shaped frame member secured to the bulged portion of said disk having its closed end designed to pivotally rest upon the upper end of said stem, a rectangular plate mounted transversely in said U-shaped member near the 35 upper ends of its parallel portions, said plate having an opening through which the stem extends, the distance between its diametrically opposite corners being substantially 40 equal to the inside diameter of said tubular support, a notch in each side edge of said plate for receiving the downwardly

extending portions of said U-shaped member, each end of said plate being provided with a downwardly extending spring member for engaging the inner surface of said tubular support. 45

2. A caster designed to be detachably mounted in one end of a tubular support comprising a yoke, a caster wheel rotatively 50 mounted in said yoke, a stem extending upwardly from said yoke, a disk pivotally mounted near the lower end of said stem and perpendicular thereto, said disk being provided with an upwardly extending bulged portion having an annular inclined 55 edge designed to fit the inner surface of said tubular support, an inverted U-shaped frame member secured to the bulged portion of said disk having its closed end designed to 60 pivotally rest upon the upper end of said stem, a rectangular plate mounted transversely in said U-shaped member near the upper ends of its parallel portions, said plate having an opening through which the 65 stem extends, the distance between its diametrically opposite corners being substantially equal to the inside diameter of said tubular support, a notch in each side edge of said plate for receiving the downwardly 70 extending portions of said U-shaped member, each end of said plate being provided with a downwardly extending spring member for engaging the inner surface of said tubular support, each of said downwardly 75 extending spring members being provided with an inwardly extending member placed in overlapping positions, both of said inwardly extending members being provided with an opening for receiving said upwardly 80 extending stem. 75

Des Moines, Iowa, November 11, 1924.

ALFRED G. HAGUE.
